UNITED STATES PATENT OFFICE

STEPHEN SLESINGER, OF NEW YORK, N. Y.

DESIGN FOR A TOY ANIMAL

Application filed January 20, 1931. Serial No. 38,390. Term of patent 7 years.

To all whom it may concern:

Be it known that I, STEPHEN SLESINGER, a citizen of the United States, residing at New York city, county of New York, and State of New York, have invented a new, original, and ornamental Design for a Toy Animal, of which the following is a specification, reference being had to the accompanying drawing, forming a part thereof.

In the drawing:

I claim:

The ornamental design for a toy animal as shown.

STEPHEN SLESINGER.
